[57] **CLAIM**

The ornamental design for the air chute deflector for a
temperature-controlled container, as shown and described.

DESCRIPTION

FIG. 1 is a reduced side elevational view of the air chute
deflector for a temperature-controlled container showing my
new design, it being understood that the broken lines are for
illustrative purposes only and form no part of the claimed
design;

FIG. 2 is a top plan view thereof;

FIG. 3 is an enlarged isometric view thereof;

FIG. 4 is a front view thereof;

FIG. 5 is an end view thereof, the opposite end view being
identical;

FIG. 6 is a top view thereof;

FIG. 7 is a rear view thereof; and,

FIG. 8 is a bottom view thereof.
